UNITED STATES PATENT OFFICE.

THOMAS C. ENTWISTLE, OF MILFORD, MASSACHUSETTS, ASSIGNOR TO
PHENIX MACHINE COMPANY, OF MASSACHUSETTS.

WARPER.

SPECIFICATION forming part of Letters Patent No. 242,617, dated June 7, 1881.

Application filed February 21, 1881. (No model.)

To all whom it may concern:

Be it known that I, THOMAS C. ENTWISTLE, of Milford, in the county of Worcester and Commonwealth of Massachusetts, have invented certain new and useful Improvements 5 in Warpers, of which the following is a specification.

My invention is an improvement in "slow-motions" for warping-machines, the object being 10 to impart a slow motion to a warping-machine, in order to prevent the breakage of the threads when the machine is being started, and also to enable the operator to turn the beam more readily to find the broken threads, and to bring 15 up the "falling" roll that is used to take up the slack from the spools when the machine is suddenly stopped in the usual way.

In warping-machines as heretofore made the slow-motion has been so constructed and organized that when the machine driven by the fast pulley is in operation in the usual way, 20 not only has the slow-motion, as a whole or entirely, been in motion, but the several parts or mechanical instrumentalities have also been 25 caused each to have its own motion, the result being that of producing great wear upon the parts forming the slow-motion. It is my object to remedy this defect, so organizing the slow-motion mechanism that while the parts 30 shall have their own proper motion when transmitting the desired slow movement to the warper-cylinder, the said mechanism shall, when the cylinder is driven from the usual fast or driving pulley, or at normal speed, have no 35 motion excepting as an entirety—that is to say, none of the parts constituting said mechanism shall in that case have movement relatively to one another; and to this end I combine with the slow-motion mechanism the usual fast or 40 driving pulley or wheel and the shaft on which said parts are mounted, means whereby, whenever power is applied to the fast pulley or wheel through the intermediary of the slow-motion mechanism, the shaft may be held stationary, so as to constitute at this time a point 45 of support for the slow-motion mechanism. These means I prefer to so arrange that they will automatically lock the shaft when power is transmitted through the slow-motion mechanism, and unlock said shaft or allow the same

to run free when power is applied directly to the fast pulley or wheel; and for this purpose I find that the simplest and most effective means, on the whole, are a pawl on the frame and a ratchet on the shaft, operating together 55 substantially as hereinafter described.

The nature of my invention, and the manner in which the same is or may be carried into effect, will be understood by reference to the accompanying drawings, in which— 60

Figure 1 is a sectional elevation of so much of a warping-machine as is needed for the purpose of explaining my invention, the slow-motion and contiguous devices being shown in vertical section, the plane of section passing through the longitudinal center of the shaft on which the devices are mounted. Fig. 65 2 is a section on line $x-x$, Fig. 1, looking in the direction of the arrow 1. Fig. 3 is a section on line $y-y$, Fig. 1, looking in the direction of the arrow 2. 70

A is a shaft extending through the pulleys B C D, the frame, and the box R, in the latter of which it has its bearing and support. B is the loose pulley. C is the intermediate or 75 slow-motion pulley. D is the fast or driving pulley. All three pulleys are loose on the shaft.

In the driving-pulley D is an internal gear, T, operating in which is the gear M, which receives its motion from the intermediate gear 80 L, driven by the gear K, which is attached to the pulley C. The gears L and M revolve on studs fastened to the counterweighted cross-head F, which is mounted on and fastened tight to the shaft A. The pawl or dog N is hinged to 85 the frame and operates in connection with the ratchet G, fast on shaft A. The gear O is fastened to and operates the shaft upon which is fixed the warper-cylinder P. The gear S is on the hub of the fast pulley D and imparts 90 motion to the gear O.

When it is desired to start the machine the belt is shifted from pulley B to the slow-motion pulley C, which gives motion to the pinion-gear K. The motion of the latter, through 95 the intermediary of the pinions L and M and internal gear, T, is transmitted to pulley D. The motion thus transmitted is a slow motion, and the intermediaries are enabled thus to act by reason of the pawl or dog N, which falls 100

in and engages the ratchet G. The tendency of the action of the gear K is to revolve the cross-head F and the shaft A, on which said cross-head is fastened, in the direction indicated by the arrow on the ratchet in Fig. 3; but this tendency is neutralized by the dog N, which brings up against the tooth or shoulder on the ratchet, and thus holds the shaft stationary. As soon, however, as the belt is shifted from the slow-motion pulley to the fast pulley D, power is applied to that pulley directly, and not through the slow-motion intermediary. The result is that the pulley D carries around the slow-motion mechanism, the shaft A revolving in a direction which permits the dog or pawl to ride over the ratchet. The slow-motion mechanism—shaft A included—now revolves as an entirety with the fast-motion pulley; but the individual parts of that mechanism are at rest with respect to one another.

The dog or stop N, as will be seen, is always in position, and is essentially automatic in action.

Having described my invention, what I claim, and desire to secure by Letters Patent, is as follows:

1. In a slow-motion mechanism for warping-machines, the combination, with the fast pulley or wheel, the slow-motion pulley or wheel, mechanism for transmitting movement from

the slow-motion to the fast pulley, and the shaft on which the same is fastened, of means, substantially as described, whereby, when motion is transmitted from the slow-motion pulley, said shaft is locked against or prevented from rotary movement, substantially as and for the purposes hereinbefore set forth. 35

2. The combination, with the fast and the slow-motion pulleys and gears carried by the same, of the cross-head, the movement-transmitting pinions mounted on the same, the shaft on which said cross-head is fastened, and an automatically-operating detent or locking mechanism, substantially as described, which locks the shaft against rotary movement at the time and in the manner substantially as set forth. 40 45

3. The combination, with the fast and the slow-motion pulleys and gears carried by the same, of the cross-head carrying intermediate pinions, the shaft to which said cross-head is fastened, and the pawl or dog and ratchet, the combination being and acting substantially as hereinbefore set forth. 50

In testimony whereof I have hereunto set my hand this 16th day of February, 1881. 55

THOMAS C. ENTWISTLE.
